CLAIM

The ornamental design for a cosmetic mirror, as shown and described.

DESCRIPTION

FIG. 1 is a top plan view showing our new design attached to a substantially round cylindrical lipstick casing using an attachment means;

FIG. 2 is a front elevation view thereof;

FIG. 3 is a left side elevation view thereof;

FIG. 4 is a right side elevation view thereof;

FIG. 5 is a bottom plan view thereof;

FIG. 6 is a top plan view showing our new design attached to a substantially square cylindrical lipstick casing using an attachment means;

FIG. 7 is a front elevation view thereof;

FIG. 8 is a left side elevation view thereof;

FIG. 9 is a right side elevation view thereof; and,

FIG. 10 is a bottom plan view thereof.

The broken line showing of the lipstick cases is for illustrative purposes only and forms no part of the claimed design.
